UNITED STATES PATENT OFFICE.

IVAR F. WARME, OF SYRACUSE, NEW YORK, AND JOHN C. TALIAFERRO, OF BALTIMORE, MARYLAND, ASSIGNORS TO CONTINENTAL CAN COMPANY, INCORPORATED, OF SYRACUSE, NEW YORK, A CORPORATION OF NEW YORK.

MULTIPLE-SPINDLE DOUBLE SEAMER.

1,306,648.

Specification of Letters Patent. Patented June 10, 1919.

Application filed September 19, 1914. Serial No. 862,626.

To all whom it may concern:

Be it known that we, IVAR F. WARME and JOHN C. TALIAFERRO, citizens of the United States, residing at Syracuse, in the 5 county of Onondaga, State of New York, and residing at the city of Baltimore and State of Maryland, have invented certain new and useful Improvements in Multiple-Spindle Double Seamers, of which the following is a description, reference being had to the accompanying drawing and to the figures of reference marked thereon.

The invention relates to new and useful improvements in an apparatus for attaching 15 the end to a can body, and more particularly to an apparatus for forming a double seam for joining the can end to the can body. While our improved apparatus is particularly adapted for joining the can end to a 20 filled can body, it may also be used for securing the bottom end to the can body.

An object of the invention is to provide in an apparatus of the above character an end seaming machine wherein a plurality of 25 rotating chucks are mounted and are held substantially fixed against radial movement relative to the carrier and wherein a seaming member is associated with the carrier and so positioned relative to the rotating 30 chucks that as the carrier rotates the can ends which have been seated in the can bodies will be moved into contact with the seaming member and withdrawn therefrom during a partial rotation of the carrier.

35 A further object of the invention is to provide an end seaming machine of the above character wherein the seaming member is in the form of a rotatable seaming roll having a seaming groove formed therein and this seaming roll is not only eccentrically mounted relative to the rotation of the carrier, but means is provided for adjusting the eccentricity of the roll so as to vary the pressure of the seaming roll against the can 40 end.

A further object of the invention is to provide an end seaming machine of the above character wherein the adjusting means for the seaming roll is so constructed 45 that the eccentricity of the roll may be varied without shifting the angular position of maximum pressure of the seaming roll against the can end.

A still further object of the invention is to provide an end seaming machine of the 55 above character wherein there is a can body receiver and can end support associated with each chuck and wherein means is provided for placing a can end on each can end support while the carrier is rotated. 60

A still further object of the invention is to provide an end seaming machine which consists of two rotating carriers, each of which is provided with a plurality of rotating 65 chucks and coöperating can supports, and wherein one carrier has a seaming roll operating simultaneously upon a plurality of can ends for performing the first operation of joining the end to the can body and wherein the other rotating carrier has a 70 seaming roll associated therewith operating simultaneously upon a plurality of can ends for performing the second operation in joining the end to the can body, together with means for transferring the cans from one 75 carrier to the other.

A further object of the invention is to provide an apparatus of the above character having two rotating carriers with means for supporting the seaming rolls of the respective carriers whereby the axes of said rolls may be adjusted relative to the axis of their respective carriers for varying the pressure of the seaming rolls on the can ends during the seaming operations. 85

These and other objects will in part be obvious and will in part be hereinafter more fully disclosed.

In the drawings which show by way of illustration one embodiment of the invention:

Fig. 18 is a plan view showing the adjustable rings having the eccentric surfaces for shifting the seaming roll.

Fig. 19 is a side view of the same.

Fig. 20 is an enlarged detail in side elevation showing the locking plate for locking the adjusting rings and the holding plate therefor together.

Fig. 21 is a similar view showing the plates shifted and locked in shifted position.

Fig. 22 is a plan view of the holding plate for the adjusting rings.

Fig. 23 is a vertical sectional view through the end feeding mechanism and also through the transferring mechanism for transferring a can from one carrier to the other.

Fig. 24 is a plan view of the end feeding mechanism and a portion of the carrier showing ends fed to the end supports on the carrier.

Fig. 25 is a vertical sectional view through one of the stacks and one of the can end supports showing the manner of feeding the can end from the stack to the support.

Figs. 26 to 30, inclusive, are views partly in section showing more or less diagram-

matically the receiver for the can bodies, the chuck, the seating pad, and a portion of the seaming roll in various positions during the forming of the end seam.

Fig. 31 is a diagrammatic view in plan showing the travel of the can through the machine and the position of the same during the various operations thereon.

Fig. 32 is a diagrammatic view showing a modified arrangement of the closing ma- 75 chines.

The invention consists generally in providing an apparatus for attaching the ends to cans wherein an end is attached to a can body by a double seam. As shown in the drawings, two end seaming machines are used in conjunction, one of which operates to form the first operation in joining a can end to a can body and the other performs the second operation in joining said can end to the can body. These end seaming machines are substantially alike with the exception that associated with one of the machines is an end feeding mechanism whereby can ends are fed to the rotating carrier therefor and supported in proper relation to the can bodies so that they may be seated therein as the can bodies and the ends are chucked for rotating the same.

Each end seaming machine consists of a 95 rotating carrier on which are mounted a plurality of rotating chucks and co-operating can supports. These chucks are carried by spindles which are mounted in spindle carriers and these spindle carriers are in 100 turn fixed to the carriers so that they are placed side by side and held from any substantial movement radial to their carriers. On each carrier is a seaming roll which is eccentrically mounted relative to the axis of 105 the carrier, and this seaming roll is so disposed relative to the traveling chucks that the can ends are successively brought into engagement therewith and moved out of contact with the seaming roll as the carrier 110 rotates. Means is provided for adjusting the eccentricity of these seaming rolls whereby the pressure of the rolls against the can ends may be varied. The two carriers preferably rotate in the same direction and 115 are slightly spaced so that a transferring mechanism may be placed between the carriers for receiving the cans from one carrier and placing the same on the other as the carriers rotate.

These end seaming machines are especially designed for securing the closing end on a filled can and also designed so that the filled cans may be received directly from a filling machine which is mounted upon 125 the same supporting base as the end seaming machines. The can support of the filling machine is located in the same plane as the can support of the closing machine so that the filled cans may be transferred from 130

one support to the other as said can supports are rotated and in order to facilitate this transfer, the can support of the filling machine rotates in a direction opposite to 5 the direction of rotation of the can support of the closing machine.

Referring more in detail to the drawings, the can machine consists of a bed plate 1 on which is mounted a filling machine which 10 may be so constructed as to fill the cans in two operations, placing in the cans in one operation the solid parts and in another operation the liquid parts. In Fig. 1 of the drawing, we have indicated at A the first operation filling machine and at B the second operation filling machine. The details of 15 this filling machine have not been illustrated except to show in full lines the can support 2 of the second operation filling machine 20 and the receivers 3 for holding the cans as they are being filled. This support 2 rotates in the direction of the arrow as indicated in this figure. Also shown in this figure are two end seaming machines indicated at C 25 and D, respectively. A transferring mechanism for transferring the cans from one end seaming machine to the other is indicated at E, while the end feeding mechanism for feeding the ends to the closing machine C is 30 indicated at F.

The two end seaming machines C and D are similar in construction except as to a few details and, therefore, a description of one of these machines will answer for the other. 35 The end seaming machine indicated at C is the first operation machine, while the end seaming machine indicated at D is the second operation machine. These two end seaming machines will be described as one 40 and like numerals applied to the parts referred to. The differences, however, between the two machines will be pointed out in connection with the detail description.

Mounted on the bed plate 1 is a supporting base 4 from which rises a column 5 on which is mounted a rotating carrier 6. This rotating carrier consists of a lower turret 7 and an upper turret 8. These two turrets are splined together so as to rotate as one. 50 The turrets are supported on ball bearings indicated at 9 and 10.

Mounted on the lower turret are a plurality of can supports 11. Each of these can supports consists of a rotatable supporting plate 12 which is secured to a spindle 13. This spindle is mounted in a sleeve 14 which extends into a recess in a supporting slide 15. A nut is threaded on the lower end of the spindle and a ball bearing 17 60 serves to support the rotatable plate 12. The thrust plate 12^a rests directly on the bearing 17 and spring 12^b engages suitable sockets in the supporting plate and the thrust plate thus providing a yielding support for the can. The lower turret is

formed with recesses 18, see Fig. 5, and in these recesses are fitted the supporting slides 15 which carry the can supports 12. Each recess opens into a larger recess 19. The recess 19 receives a plate 20 which closes the 70 recess 18. The turret 7 is formed with gear teeth 21. The plates 20 are also formed with gear teeth 21 and these gear teeth serve as a means for rotating the turret. The plates 20 are bolted in place by suitable bolts 75 22 and the gear teeth are cut after the plates are fixed to the turret. The means for rotating the turret will be described later.

The supporting slide 15 carries a stud 24 at its lower end and this stud is provided 80 with a roller 25 which engages a cam groove 26 in a collar 27. The collar 27 is splined to the supporting base so that it is held from rotation and as the turret rotates therefore, the roller 25 will be caused to travel in the 85 groove 26. The collar 27 is shown in plan view in Fig. 14, and in side elevation in Fig. 15. The lower part of the collar 27 is provided with a thread 28. The supporting base 4 is also threaded at 29. These threads 90 28 and 29 are respectively right and left hand threads. A ring 30 engages the threads 28 and 29 and by turning this ring the collar 27 is raised and lowered. The ring is provided with suitable recesses 31 whereby it 95 may be rotated. The groove 26 which engages the roller 25 is formed with an upper section 32 and a lower section 33. As the turret rotates the roller 25 will pass from one section to the other of the cam groove 100 and thus raise and lower the can supports. The purpose of this movement of the can support is to raise the filled can into contact with the can end which is to close the same and bring the can end into contact 105 with the rotating chuck for clamping the can body and can end and rotating the same as it is presented to the seaming roll. By shifting the collar 30 the position of the supporting plates 12 may be varied. By 110 this shifting of the plates, cans of varying heights may be closed on the machine.

Mounted on the turret and forming a supporting table is a filler plate 34. This plate is provided with openings 35 adapted to 115 receive the can supports 12. The plate may be secured to the turret by suitable screws passing through openings 36. As clearly shown in Fig. 17, these filler plates may be removed and replaced by a filler plate of 120 greater thickness as indicated in dotted lines in this figure when the can support 12 is adjusted to a new position.

The filler plate forms a table, the upper surface of which is flush with the upper 125 surface of the can supports when said can supports are in their lower position. This permits the filled cans to be readily slid on to the table and on to the can supports without spilling the contents thereof.

Coöperating with the can support 12 is a rotary chuck 38. This rotary chuck is secured to a spindle 39 which is in the form of a sleeve. The spindle 39 is journaled in a spindle carrier 40. Said spindle is provided with a ball end thrust bearing 41 adjacent its lower end and a ball lateral thrust bearing 42. Said spindle is also provided with an end thrust bearing 43 and a lateral thrust bearing 43^a adjacent the upper end thereof. Fixed to the upper end of the spindle is a pinion 45. This pinion meshes with a gear 46. The gear 46 is splined to a shaft 47 which is mounted in a suitable bearing 48 carried by the supporting base 4. The shaft extends upward through the column 5 and is mounted in a bearing 49 at the upper end of the column. This shaft is rotated by a suitable gear 50 at the lower end thereof. The gear 50 meshes with a gear 51 secured to a shaft 52 which is mounted in a bracket 53 carried by the bed plate. The gear 51 meshes in turn with a gear 54, and this gear 54 carries also a beveled gear 55 which meshes with a beveled gear 56 on the main shaft, and the main shaft is rotated by a suitable motor 57 which is mounted on the supporting bed. The gear 54 is attached to the central shaft of the first operation machine, while the gear 50 is attached to the central shaft of the second operation machine and, therefore the shaft of the second operation machine is driven from the shaft of the first operation machine through the intermediate gear 51.

The rotating spindle which carries the chuck is in the form of a sleeve and extending through this sleeve is a rod 58 which carries a seating pad 59 at the lower end thereof. This seating pad is normally housed in a recess in the under face of the chuck. This rod 58 is held from rotation but is reciprocated longitudinally in the spindle sleeve. This is accomplished by a sleeve 60 which is fixed to the upper end of the rod 58 and carries a roller 61 which runs in a cam groove 62 in a cap plate 63. The cap plate is carried by a sleeve 64 which surrounds the upper end of the shaft 47. The cap plates of the two machines are joined by a bar 65, which bar is bolted to the cap plates by bolts 66. This bar encircles the projecting sleeve 64 of the cap plate 63 and one cap plate locks the other through this connecting bar from rotation. There is a collar 67 secured to the upper end of the shaft 47. The collar 60 is also provided with an arm 68. This arm 68 is forked at its outer end so as to form a recess 69 adapted to receive a lug 70 projecting from the adjacent collar 60. These arms 68 through the forked construction of the outer end thereof and the interlocking lug 70 lock all the rods against rotation, but inasmuch as the side walls of the lugs 70 are vertical, they permit each rod

to be moved endwise independent of the others.

As the carrier consisting of the upper and lower turret rotates the roller 61 travels in the cam groove 62 and at times causes the rod 58 to be moved endwise. This groove is so shaped as to cause the proper movements of the seating pad. The seating pad is first moved down against the can end which is held by a can end support underneath the chuck and the seating pad rests against the can end until the can body is raised and forced on to the can end, that is the can end is seated in the can body, after which the seating pad rises with the can end and can body holding the can end seated until the can end is received by the chuck. The seating pad is then withdrawn from contact with the can end and held out of contact therewith while the chuck is rotating the can end and can body and forming the end seam. After the end seam is formed the seating pad moves down with the can support and becomes a stripper for stripping the can end from the chuck. The cam groove 62, therefore, is formed with an upper and lower level section, the lower level section operating to hold the seating pad in engagement with the end during the seating thereof while the upper level holds the seating pad out of engagement with the can end. There is also in this cam groove a knock out section which operates the seating pad to strip the can from the chuck. The only difference between these cans in the first and second operation machines is that in the second operation machine this lower level is omitted for the reason that when the cans are fed into the second operation machine the ends are secured thereto and, therefore, no seating operation of the pad is necessary. In other words, the seating pad in this machine is solely a stripper for stripping the can from the chuck.

The spindle carriers are in the form of sleeves with suitable recesses formed therein for the bearings for the chuck spindle. The mountings for these spindle carriers are shown in detail in Figs. 6 and 7. Each spindle carrier is provided with a rearwardly extending web 71 which fits into a recess 72 in the upper turret 8. Adjacent the upper end of the spindle carrier is a perforated lug 73. A bracket 74 is secured by a bolt 75 to the upper face of the outer turret 8, and this bracket is provided with spaced arms 76 which receive the lug 73 and a pintle 77 passing through the arms 76 and the lug 73 forms a hinged connection for supporting the upper end of the spindle carrier. The spindle carrier at the lower end is secured to the turret by bolts 78 and 79. These bolts extend through perforated lugs 80 projecting from the spindle carrier 40. Each bolt is threaded into the turret and is

provided with a limiting collar 81. The lugs 80 are recessed at 82 to receive these limiting collars, and these recesses are slightly deeper than the thickness of the collar. A 5 cap plate 83 engages over the outer end of each of the bolts 78 and a cap screw 84 extending through the cap plate 83 is threaded into the outer end of the bolt. In the first 10 operation machine, it is desirable that these spindles shall be absolutely fixed against any radial movement and these cap plates in this machine, as shown in Fig. 12, are solid and firmly hold these spindle carriers against their seats on the turret. 15 In the second operation machine, however, these spindle carriers should yield slightly to permit the side seam to pass the seaming roll without undue pressure thereon. This is accomplished by the construction 20 shown in Fig. 11. The cap plate 83 is recessed on its inner face and a yielding washer 85 is interposed between this cap plate and a washer 86 which bears against the outer face of the lug 80. This yielding 25 washer 85 permits a slight outward movement of the lower end of the spindle carrier, the upper end of the spindle carrier swinging about the hinged support therefor.

This spindle carrier not only serves as a 30 means for supporting the spindles for the chucks but also serves as a means for supporting the can ends and as a means for supporting the receivers for the can bodies which centers the same underneath the 35 chuck. To this end, the spindle carriers project downward below the chuck, see Figs. 8 and 9. The lower part of the spindle carrier is formed with a can receiver 87. This can receiver has an inwardly projecting face 40 which is curved to conform substantially to the curvature of the can body and the front side is open so that the can body may be fed into the receiver. The receiver above the projecting surface 88 is cut away, as at 45 89, to form sufficient space for the flange of the can body. Above the receiver is a can end seat 90. The spindle carrier is formed with a flat projecting ledge 91 on to which the can ends are fed and from this projecting 50 ledge the can ends are moved back on to the can end seat 90. Directly beneath the can end seat is a tapered opening 92. This can end seat is below the chuck and the spindle carrier is cut away at 93 to form a 55 clearance space in which the chuck rotates.

The spindle carrier is also cut away at 94 to permit the seaming roll to project through and engage the can end when the same is engaged by the chuck. The can ends are fed on 60 to the can end supports after which the can bodies are fed into the receivers and then the can bodies are raised into engagement with the can ends and the can ends carried into engagement with the chucks which rotate the 65 can ends and can bodies as they are now

clamped between the rotating chucks and the can supports, and as they are rotated they are gradually carried into engagement with the seaming roll.

The one difference between the spindle 70 carriers in the first and second operation machines as to the features just described, consists in the fact that in the second operation machine there is no seat for the can end and the spindle carriers are projected 75 downwardly solely for the purpose of providing a receiver for the cans which operates to center the can underneath the chucks. As the cans are received into the second operation machine with the ends joined thereto, 80 there is no purpose in the can end supports or tapered ring except to guide the can into engagement with the rotating chuck. The seaming roll is indicated at 95. Said seaming roll surrounds the central column and 85 also the lower turret and is formed with a seaming groove 96 which is of uniform cross section throughout the entire circumference of the seaming roll. Said seaming roll consists of a supporting sleeve 97 from which 90 projects a rib or disk 98 having the seaming groove 96 formed in the outer face thereof. This rib or disk 98 is intermediate the ends of the sleeve 97.

At the inner face of the sleeve 97 is located 95 a roller bearing 98'. The rollers of the roller bearing are mounted in suitable plates 99. Above and below the ends of the sleeve 97 are ball bearings 100. Between the roller bearing 98' and the turret 7 are two rings 100 101 and 102. These rings are shown in detail in Figs. 2, 4 and 18 to 21, inclusive. The inner surface of the inner ring 102 is concentric to the axis of the rotating carrier and is fitted to turn freely on the lower rotating 105 turret 7. The outer surface of this ring, indicated at 103, is eccentric to the axis of rotation of the carrier. The inner surface of the outer ring 101 which contacts with the surface 103 is also eccentric to the axis of rotation of the carrier or lower turret, while the outer surface 104 of the outer ring is eccentric to the inner surface of this outer ring. The roller bearings engage the outer 110 surface of the outer ring. The inner ring is 115 provided with a projecting flange 105, while the outer ring is provided with a projecting flange 103. The flanges are formed with spaced grooves 107 and 108, respectively. These grooves may be graduated or provided 120 with suitable indicating marks.

Beneath the rings is a holder 108'. This holder 108' rests on a ledge on the lower turret 7 and the rings and holder are placed between this ledge and the lower end of the 125 upper turret 8. A collar 109 is threaded on to the upper end of the outer ring and overlies the bearings for the seaming roll. The holder 108' is provided with an outwardly projecting arm 110 which is suitably bolted 130

to the frame of the machine so as to prevent the holder from rotating. This holder is provided with a groove 111.

5 A locking plate 112 is formed with a rib 113 which is adapted to engage the grooves in the flanges of the rings and the groove 111 in the outer edge of the holder 108'. A screw 114 passes through said plate 112 and clamps the same to the holder 108'.

10 From the above construction, it will be apparent that the seaming roll is mounted so that it may rotate freely about the rings 101 and 102, but owing to the eccentric surfaces of these rings the axis of the seaming roll is eccentric to the axis of the rotating carrier. Inasmuch as the rotating chucks and coöperating can supports are mounted to rotate about axes which are substantially radially fixed, the seaming roll may be adjusted 15 so that as the carrier rotates, the can ends will be caused to engage the seaming roll and move out of engagement therewith. The eccentricity of this seaming roll may be varied by adjusting the rings 101 and 102.

20 This is accomplished by removing the plate 112 and turning the rings until the proper grooves are brought into register with the groove 111, after which the plate is replaced.

25

30 By adjusting both of the rings and by adjusting the same in opposite directions, the axis of the seaming roll may be shifted toward and from the center of the carrier in a radial direction, that is, without shifting laterally the position of the maximum pressure. By adjusting one ring alone, or by adjusting both rings in the same direction, the position of maximum pressure may be varied. The only difference between the 35 40 seaming rolls in the first operation machine and in the second operation machine resides in the shaping of the groove. These rolls are in each instance similarly mounted and similarly adjusted.

45 The cans are transferred from one seaming machine to the other by the transferring mechanism indicated at E. Between the supporting bases of the two machines, there is a supporting bracket 53 in which the 50 shaft 52 is mounted. This bracket carries a table 115 on which is mounted a supporting and guiding plate 116 which is shaped to fill the space between the rotating tables of the end seaming machines so that a can 55 may be moved from one machine on to this supporting plate and from the supporting plate on to the table of the other machine. The upper face of this plate is kept substantially flush with the upper face of the filler 60 plate of the end seaming machines. This can be accomplished by changing the plates 116.

At the upper end of the shaft 52 is loosely mounted a rotating disk 117 which has segmental pockets 118 shaped to conform to the

can bodies. These pockets form of the disk in effect a star wheel. Secured to the disk is a gear 119. This gear meshes with a gear 120 on a vertical countershaft 121. A gear 122 is connected to the gear 120 and running idle on the shaft 121 meshes with a gear 123 which is splined to the shaft 52. These gears are so proportioned that the timing of the travel of the can body on the plate 116 is substantially the same as the 75 travel of the can body when on either carrier. Also splined to the shaft 52 is a gear 124 and this gear meshes with the gear teeth 21 on the carrier of each end seaming machine. The rotation of the shaft 52, therefore, will cause the two carriers to rotate in unison and each in a counterclockwise direction as viewed in Fig. 1. The guide plate 116 is provided with curved projecting arms 125 and 126 which extend respectively over the supporting tables of the carrier. When the can reaches the arms 125, it will be moved gradually forward through the action of the rotating star wheel and the rotating carrier on to the plate 116. The 80 85 rotating star wheel will carry the can along the plate, and the guide rail of the plate, together with the arm 126, will direct the can so that it is moved into the receiver of the second operation machine. 90 95

As above noted, the speed of the star wheel is such that the travel of the cans while in the end seaming machines, and from one end seaming machine to the other is uniform. 100

The means for feeding the can ends on to the can end supports of the first operation machine C is indicated at F in the drawings. The intermediate frame forming the bracket 53 has an extension 127. On this 105 extension are mounted two stack holders 128 and 129. The can ends are stacked in these holders. Each holder consists of a base ring 130 and spaced rods 131 which are mounted therein. This base ring is raised from the 110 support 132 attached to the upper end of the extension 127 so as to permit a slide 133 to pass beneath the same. This slide carries a separating plate 134.

As clearly shown in Fig. 25 of the drawings, when the slide moves forward, the separating plate 134 will separate the lowermost can end from the stack and will force the same from the stack holder on to the supporting ledge of the spindle carrier 120 40 and part way on to the can end seat for the can end. As the carrier rotates, a yielding guide finger 135 which is fixed to the supporting plate 127 engages the can end and crowds it back on to its seat directly 125 underneath the rotating chuck. There is a reciprocating slide 133 for each stack holder. These slides are mounted so as to reciprocate in guiding grooves in the upper face of the supporting plate 132. A yoke 130

136 projects underneath the supporting plate 132 and reciprocates back and forth on said supporting plate. This yoke is bolted by suitable bolts 137 to the slides 133. 5 Mounted in the extension 127 is a shaft 138. This shaft at its lower end carries a gear 139 which meshes with a gear 140 carried by said extension, and the gear 140 meshes with the teeth 21 of the rotating carrier of 10 the second operation machine. At the upper end of the shaft 138 there is a flange 141 which is fixed to the shaft. Freely mounted on the shaft is a disk 142. This disk and flange are provided with suitable hardened 15 sleeves 143 into which is adapted to be placed a pin or nail 144. The disk 142 carries a roller 145 which engages a cam groove 146 formed in the yoke 136. This cam groove is so shaped that while the shaft 138 20 rotates at a uniform speed, the slides for conveying the can ends to the carrier will be quickly moved forward to project the can ends from the stacks on to the rotating carrier. The purpose of the connecting pin 25 144 is to provide a breakable connection in the operating mechanism for the end feeding devices so that if for any reason the can ends become stuck, the pin will break and thus prevent the breaking of any part of the 30 operating mechanism.

The end feed is so timed that a can end will be taken from each stack and simultaneously moved forward on to the can end seats of the first operation machine and 35 when the next two receivers are in front of the stack holders, two more can ends will be delivered from the stacks on to the can end seats of said receivers.

The operation of joining the can ends to 40 the can bodies will be made clear from the diagrammatic views contained in Figs. 26 to 31 inclusive. The path of travel of the can bodies is indicated by the broken line and the arrows in Fig. 31. In full lines is 45 indicated the surface of the seaming roll. When a receiver of the first operation machine is at the radial line *a*, the can supports are at their lower level and at this point the can ends are fed on to the can end 50 supports. The upper surface of the table of this end seaming machine, and the upper surface of the table of the filling machine are in the same plane, and a guide rail 145^a 55 operates to crowd the cans from the receivers 3 of the filling machine into the receivers of the end seaming machine.

At the radial line *b*, Fig. 31, the filled can is fully seated on the can support and the can support is raised through the action of 60 the fixed cam 26 on the roller 24. Prior to the lifting of the filled cans the seating pad is lowered into engagement with the can end on the can end support.

In Fig. 26 of the drawings, I have shown 65 diagrammatically a can body being raised

and the seating pad being lowered so as to contact with the can end and support the same while it is being seated in the can body. After it is seated in the can body, as 70 shown in Fig. 27, the seating pad retracts and allows the can end and can body to be raised and chucked as indicated in Fig. 28. This all occurs at or near the radial line *b*.

When the radial line *c* is reached the can end begins to make contact with the seaming roll. This is brought about through the eccentric positioning of the seaming roll. The contact will be first very light and this will increase to a maximum pressure which rolls the flange of the can end and the flange 80 of the can body into the first operation of joining the end to the body.

When the radial line *d* is reached the can end is free of the seaming roll and soon after this position is reached the can support drops to its lower position so that the can bottom is flush with the table of the carrier. The arm 125 now engages the can and transfers the same on to the supporting plate 116. The star wheel 117 which is positively driven engages the can and assists in carrying the same along the guide rail on to the supporting plate, transfers it across the supporting plate and onto the receiving table of the second operation machine. In 90 Fig. 29 of the drawings, we have shown the position of the seaming roll when finishing the seam. After the seaming roll is out of contact with the same and when the can support is lowered, the seating pad is given 100 a downward push which knocks the can from the chuck, as shown in Fig. 30. This occurs at or near the radial line *d*.

The operation of the second operation machine is similar to that above described. 105 After the can is fully seated on the can support, it is raised so as to cause the can to engage the chuck. This occurs at the radial line *f*. As the carrier rotates the end seam will make contact with the seaming roll, engaging the same lightly first and the pressure increasing to maximum pressure. This is due to the eccentric seating of the seaming roll relative to the path 110 of travel of the chucks. After the seam is formed, the can end will be gradually withdrawn from the seaming roll and at the radial line *e*, Fig. 31, it will be out of contact with the seaming roll, after which the can support is lowered and the seating pad 115 is given a knocking movement to strip the can from the chuck. The closed cans are removed from the second operation machine by the engagement of the same by the arm 120 110 of the holding plate 108.

The carrier of each end seaming machine is provided with a groove which engages a rib 147 on the actuating gear 124. This rib serves to determine the proper alignment of the carriers of the two machines. There 130

is also preferably a suitable interlocking between the carrier of the first operation end seaming machine and the carrier of the second operation filling machine. Each 5 chuck is also provided with a groove 148 which receives a rib 149 on the seaming roll. This interlocking of the seaming roll with the chuck prevents endwise movement of the chuck relative to the seaming roll and 10 insures a proper positioning of the flange of the can end for the seaming groove.

While we have described a complete organized mechanism for closing filled cans, it will be obvious that the end seaming 15 machine herein shown and described may be used for attaching a can end to the bottom of a can body, that is in the forming of open top cans, as well as for placing the closing end on a can body. If the end 20 seaming machine herein shown be used solely for end seaming purposes in the construction of cans, the rotating carriers may be horizontal instead of vertical.

Instead of having an intermediate transferring mechanism for transferring the cans 25 from one closing machine to the other we may operate the closing machines so as to feed direct from one to the other. In Fig. 32 of the drawings we have shown diagrammatically two closing machines C and D placed side by side and geared together so that one turns in a counter-clockwise direction while the other turns in a clockwise direction. In order that these closing machines 35 may feed directly from one to the other they must, however, be made larger in diameter and a greater number of operating spindles or the spindles placed relative to each other so as to give a sufficient time 40 for the first operation before the can is transferred to the second closing machine.

The radial line *b* in this figure indicates the position where the can is chucked and the radial line *d* indicates the position where 45 the can is released from the seaming head. The line *A'* indicates the path of travel of the can from the filling machine to the first operation closing machine and the line *B'* indicates the path of travel of the cans to 50 the second operation closing machine. The radial line *f* indicates the position of the cans when chucked in the second operation machine and the radial line *e* in this figure indicates the position where the cans are 55 discharged. The arrows on this figure indicate the direction of rotation of the different machines.

While we have shown and described two 60 end seaming machines operating in succession for forming an end seam, it will be obvious that many of the features described may be used in connection with an end seaming machine wherein both operations are performed in the same machine. 65 It is also obvious that minor changes in

the details of construction and arrangement of parts may be made without departing from the spirit of the invention as set forth in the appended claims.

Having thus described our invention, what 70 we claim as new and desire to secure by Letters Patent is:

1. An end seaming machine including in combination a rotating carrier, a plurality of rotating chucks and coöperating can body 75 supports, and means for placing a can end between each chuck and support as the carrier rotates, means for seating the can ends in the can bodies, the axes of said rotating chucks being substantially radially fixed relative to the axis of the carrier, a seaming 80 member having a seaming groove formed therein, said seaming member being set eccentrically to the axis of rotation of the carrier whereby the can ends are moved into 85 and out of contact therewith as the carrier rotates.

2. An end seaming machine including in combination a rotating carrier, a plurality of rotating chucks and coöperating can body 90 supports, means for placing a can end between each chuck and support as the carrier rotates, means for seating the can ends in the can bodies, the axes of said rotating chucks being substantially radially fixed 95 relative to the axis of the carrier, a seaming member having a seaming groove formed therein, said seaming member being set eccentrically to the axis of rotation of the carrier whereby the can ends are moved 100 into and out of contact therewith as the carrier rotates, and means for adjusting the eccentricity of said seaming member.

3. An end seaming machine including in combination a rotating carrier, a plurality 105 of rotating chucks and coöperating can body supports, means for placing a can end between each chuck and support as the carrier rotates, means for seating the can ends in the can bodies, the axes of said rotating 110 chucks being substantially radially fixed relative to the axis of the carrier, a seaming member having a seaming groove formed therein, said seaming member being set eccentrically to the axis of rotation of the carrier whereby the can ends are moved into 115 and out of contact therewith as the carrier rotates, and means for adjusting the eccentricity of said seaming member, said last named means including two rings having eccentric surfaces whereby the movement of said rings in opposite directions will vary the eccentricity of said seaming member without varying the radial position of maximum eccentricity.

4. An end seaming machine including in combination a rotating carrier, a plurality of rotating chucks and coöperating can body supports, and means for placing a can end between each chuck and support as the car- 120 125 130

rier rotates, means for seating the can ends in the can bodies, the axes of said rotating chucks being substantially radially fixed relative to the axis of the carrier, a seaming 5 roll, means for mounting said seaming roll whereby the same may be freely rotated, said seaming roll having its axis eccentric with the axes of the carrier whereby the can end after it is seated in the can body will be 10 caused to engage the groove in the seaming roll and be withdrawn therefrom while the carrier is making a partial rotation.

5. An end seaming machine including in combination a rotating carrier, a plurality 15 of rotating chucks and coöperating can body supports, means for placing a can end between each chuck and support as the carrier rotates, means for seating the can ends in the can bodies, the axes of said rotating 20 chucks being substantially radially fixed relative to the axis of the carrier, a seaming roll, means for mounting said seaming roll whereby the same may be freely rotated, said seaming roll having its axis eccentric 25 with the axes of the carrier whereby the can end after it is seated in the can body will be caused to engage the groove in the seaming roll and be withdrawn therefrom while the carrier is making a partial rotation, and 30 means for adjusting radially the axis of the seaming roll relative to the axis of the carrier.

6. An end seaming machine including in combination a rotating carrier, a plurality 35 of rotating chucks and coöperating can body supports, means for placing a can end between each chuck and support as the carrier rotates, means for seating the can ends in the can bodies, the axes of said rotating 40 chucks being substantially radially fixed relative to the axis of the carrier, a seaming roll, means for mounting said seaming roll whereby the same may be freely rotated, said seaming roll having its axis eccentric 45 with the axes of the carrier whereby the can end after it is seated in the can body will be caused to engage the groove in the seaming roll and be withdrawn therefrom while the carrier is making a partial rotation, and 50 means for adjusting radially the axis of the seaming roll relative to the axis of the carrier, said means including two rings having eccentric surfaces, means for holding 55 said rings from rotation, and means whereby said rings may be adjusted relative to their holding means for shifting radially the axis of the seaming roll relative to the axis of the carrier.

7. An end seaming machine including in combination a rotating carrier, a plurality 60 of rotating chucks and coöperating can supports mounted in said carrier, the axes of said rotating chucks being substantially radially fixed relative to the axis of the carrier, means for causing a relative movement

between the rotating chuck and can support for clamping a can end on the can body, a seaming roll located within a circle, described by said rotating chucks, means for supporting said roll with its axis eccentric 70 to the axis of the carrier whereby the can ends will be caused to engage said roll and withdrawn from engagement therewith in a partial rotation of the carrier, and means for adjusting the position of the axis of the 75 seaming roll relative to the carrier, said means including two rings having eccentric surfaces, means for holding the rings from rotation, and means for adjusting the position of the rings relative to the holding 80 means.

8. An end seaming machine including in combination a rotating carrier, a plurality of rotating chucks and coöperating can supports mounted on said carrier, a receiver for 85 the can body associated with each chuck, a can end support in each receiver, means for feeding a can end on to the can end support as the carrier rotates, said receivers and chucks being substantially radially fixed 90 relative to the axis of the carrier, means for moving the can supports for seating the can ends in the can bodies and causing the same to engage the chucks, a seaming roll located within a circle described by the chucks, and 95 means for supporting said seaming roll with its axis eccentric to the axis of the carrier whereby the can ends are caused to engage and be withdrawn from the seaming groove in the seaming roll during a partial rotation 100 of the carrier.

9. An end seaming machine including in combination a rotating carrier, a plurality of rotating chucks and coöperating can supports mounted on said carrier, a receiver for 105 the can body associated with each chuck, a can end support in each receiver, means for feeding a can end on to the can end support as the carrier rotates, said receivers and chucks being substantially radially fixed 110 relative to the axis of the carrier, means for moving the can supports for seating the can ends in the can bodies and causing the same to engage the chucks, a seaming roll located within a circle described by the chucks, means for supporting said seaming roll with its axis eccentric to the axis of 115 the carrier whereby the can ends are caused to engage and be withdrawn from the seaming groove in the seaming roll during a partial rotation of the carrier, said means for moving the can end supports including a fixed cam, and means for adjusting the position of said cam for varying the position of 120 said can supports when the cans are in engagement with the chucks.

10. An end seaming machine including in combination a rotating carrier, a plurality of rotating chucks and coöperating can supports mounted on said carrier, the axis of 130

said chucks being substantially radially fixed relative to the carrier, a can body receiver for each chuck, each receiver having a can end support for supporting a can end 5 between the chuck and the can body, a seating member associated with each chuck, means for holding said seating members from rotation about the axis of its respective chuck, means for moving said member 10 so as to engage the can end and support the same as it is seated in the can body, said means including devices for moving the seating member to eject the can end from the chuck after it is joined to the can body, 15 means for moving the can supports to cause the can body to engage the can end and seat the can end against said chuck, and a seaming roll operating simultaneously on a plurality of can ends for joining the same to 20 the can body.

11. An end seaming machine including in combination a rotating carrier, a plurality of rotating chucks and coöperating can supports mounted on said carrier, the axis of 25 said chucks being substantially radially fixed relative to the carrier, a can body receiver for each chuck, each receiver having a can end support for supporting a can end between the chuck and the can body, a seating member associated with each chuck, means for holding each of said seating members from rotation about the axis of its respective chuck, means for moving said member so as to engage the can end and support 30 the same as it is seated in the can body, said means including devices for moving the seating member to eject the can end from the chuck after it is joined to the can body, means for moving the can supports to cause 35 the can body to engage the can end and seat the can end against said chuck, and a seaming roll operating simultaneously on a plurality of can ends for joining the same to the can body, means for supporting said 40 seaming roll with its axis eccentric to the axis of the carrier.

12. An end seaming machine including in combination a rotating carrier, a plurality of rotating chucks and coöperating can supports mounted on said carrier, the axis of 50 said chucks being substantially radially fixed relative to the carrier, a can body receiver for each chuck, each receiver having a can end support for supporting a can end 55 between the chuck and the can body, a seating member associated with each chuck, means for holding each of said seating members from rotation about the axis of its respective chuck, means for moving said member 60 so as to engage the can end and support the same as it is seated in the can body, said means including devices for moving the seating member to eject the can end from the chuck after it is joined to the can body, 65 means for moving the can supports to cause

the can body to engage the can end and seat the can end against said chuck, a seaming roll operating simultaneously on a plurality of can ends for joining the same to the can body, means for supporting said seaming 70 roll with its axis eccentric to the axis of the carrier, said means including two rings having eccentric surfaces, means for holding said rings from rotation, and means for adjusting the rings in opposite directions relative to the holding means whereby the axis of the seaming roll may be adjusted radially relative to the axis of the carrier.

13. An end seaming machine including in combination a rotating carrier, a plurality 80 of rotating chucks and coöperating can supports mounted on said carrier, means for feeding can ends to said carrier, means for seating the can ends in the can bodies and for clamping the same between the rotating 85 chucks and can supports, a seaming roll operating upon the can ends during the partial rotation of the carrier for performing the first operation of joining the can end to the can body, a second rotating carrier for 90 receiving the cans from the first carrier, a plurality of chucks and can receivers mounted on said second carrier, means for clamping the cans between said supports and said chucks, and a seaming roll associated with 95 said second carrier for engaging the can ends during a partial rotation of said second carrier for performing the second operation in joining the can end to the can body.

14. An end seaming machine including in combination a rotating carrier, a plurality of rotating chucks and coöperating can supports mounted on said carrier, means for feeding can ends to said carrier, means for seating the can ends in the can bodies and for clamping the same between the rotating 100 chucks and can supports, a seaming roll operating upon the can ends during the partial rotation of the carrier for performing the first operation of joining the can end to the can body, a second rotating carrier for 105 receiving the cans from the first carrier, a plurality of chucks and can receivers mounted on said second carrier, means for clamping the cans between said supports and said chucks, and a seaming roll associated with said second carrier for engaging the can ends during a partial rotation of said second carrier for performing 110 the second operation in joining the can end to the can body, a rotating chuck on each carrier being substantially radially fixed relative to the axes of their respective carriers, and the seaming rolls of each carrier 115 having their axes eccentrically set relative to the axes of their respective carriers.

15. An end seaming machine including in combination a supporting column, a carrier mounted for rotation on said column, a carrier 120

- rality of spindle carriers mounted on said carrier and arranged side by side and held substantially fixed relative to the carrier, a rotating spindle mounted in each spindle carrier, a chuck carried at the lower end of each spindle, said spindle carrier having a can body receiver and a can end support, a can support associated with each spindle, and a seaming roll adapted to project 5 through a slot in the spindle carrier and engage the can end for joining the same to the can body as the carrier rotates.
16. An end seaming machine including in combination a supporting column, a carrier 15 mounted for rotation on said column, a plurality of spindle carriers mounted on said carrier and arranged side by side and held substantially fixed relative to the carrier, a rotating spindle mounted in each spindle 20 carrier, a chuck carrier at the lower end of each spindle, said spindle carrier having a can body receiver and a can end support, a can support associated with each spindle, a seaming roll adapted to project through a 25 slot in the spindle carrier and engage the can end for joining the same to the can body as the carrier rotates, and means for supporting said seaming roll with its axis eccentric to the axis of the carrier.
- 30 17. An end seaming machine including in combination a supporting column, a carrier mounted for rotation on said column, a plurality of spindle carriers mounted on said carrier and arranged side by side and held 35 substantially fixed relative to the carrier, a rotating spindle mounted in each spindle carrier, a chuck carrier at the lower end of each spindle, said spindle carrier having a can body receiver and a can end support, a can support associated with each spindle, a seaming roll comprising a supporting sleeve 40 and a projecting disk having a seaming groove in its outer edge, roller bearings for said sleeve, and means for supporting said 45 bearings including two rings having eccentric surfaces, means for holding said rings from rotation, and means whereby said rings may be adjusted to vary the position of the axis of rotation of the seaming roll relative 50 to the axis of the carrier.
18. An end seaming machine including in combination a supporting column, a carrier mounted for rotation thereon, a plurality of spindle carriers, means for pivotally supporting said spindle carriers at the upper 55 ends thereof on said rotating carrier, means for clamping the lower ends of said spindle carriers against said rotating carriers, a rotating spindle in each spindle carrier, a 60 chuck mounted on each spindle, a coöperating can support for each chuck, and a seaming roll mounted within a circle described by said rotating chucks and having its axis set eccentric to the axis of the rotating carrier.
- 65 19. An end seaming machine including in combination a supporting column, a carrier mounted for rotation thereon, a plurality of 70 spindle carriers, means for pivotally supporting said spindle carriers at the upper ends thereof on said rotating carrier, means for clamping the lower ends of said spindle carriers against said rotating carriers, a rotating spindle in each spindle carrier, a chuck mounted on each spindle, a coöperating can support for each chuck, a seaming 75 roll mounted within a circle described by said rotating chucks and having its axis set eccentric to the axis of the rotating carrier, each spindle carrier having a receiver for the can body for centering the same underneath the chuck, and a can end support for supporting a can end.
20. An end seaming machine including in combination a supporting column, a carrier mounted for rotation thereon, a plurality of 80 spindle carriers, means for pivotally supporting said spindle carriers at the upper ends thereof on said rotating carrier, means for clamping the lower ends of said spindle carriers against said rotating carriers, a rotating spindle in each spindle carrier, a chuck mounted on each spindle, a coöperating can support for each chuck, a seaming 85 roll mounted within a circle described by said rotating chucks and having its axis set eccentric to the axis of the rotating carrier, each spindle carrier having a receiver for the can body for centering the same underneath the chuck, and a can end support for supporting a can end.
21. An end seaming machine including in combination a supporting column, a carrier mounted for rotation thereon, a plurality of 90 spindle carriers, means for pivotally supporting said spindle carriers at the upper ends thereof on said rotating carrier, means for clamping the lower ends of said spindle carriers against said rotating carriers, a rotating spindle in each spindle carrier, a chuck mounted on each spindle, a coöperating can support for each chuck, a seaming 95 roll mounted within a circle described by said rotating chucks and having its axis set eccentric to the axis of the rotating carrier, each spindle carrier having a receiver for the can body for centering the same underneath the chuck, a can end support for supporting a can end, and means for moving the 100 can supports for causing the can bodies to engage the can ends and the can ends to engage the chucks.
22. An end seaming machine including in combination a supporting column, a carrier mounted for rotation thereon, a plurality of 105 spindle carriers, means for pivotally supporting said spindle carriers at the upper ends thereof on said rotating carrier, means for clamping the lower ends of said spindle carriers against said rotating carriers, a rotating spindle in each spindle carrier, a chuck mounted on each spindle, a coöperating can support for each chuck, a seaming 110 roll mounted within a circle described by said rotating chucks and having its axis set eccentric to the axis of the rotating carrier, each spindle carrier having a receiver for the can body for centering the same underneath the chuck, a can end support for supporting a can end, and means for moving the can supports for causing the can bodies to engage the can ends and the can ends to engage the chucks, said carrier having a supporting table with recesses therein for said 115 can supports whereby the upper surface of the can supports are flush when lowered with the upper surface of the table.
23. An end seaming machine including in combination a supporting column, a carrier mounted for rotation thereon, a plurality of 120 spindle carriers, means for pivotally supporting said spindle carriers at the upper ends thereof on said rotating carrier, means for clamping the lower ends of said spindle carriers against said rotating carriers, a rotating spindle in each spindle carrier, a chuck mounted on each spindle, a coöperating can support for each chuck, a seaming 125 roll mounted within a circle described by said rotating chucks and having its axis set eccentric to the axis of the rotating carrier, each spindle carrier having a receiver for the can body for centering the same underneath the chuck, a can end support for supporting a can end, and means for moving the can supports for causing the can bodies to engage the can ends and the can ends to engage the chucks, said carrier having a supporting table with recesses therein for said can supports whereby the upper surface of the can supports are flush when lowered with the upper surface of the table.
24. An end seaming machine including in combination a supporting column, a carrier mounted for rotation thereon, a plurality of 130 spindle carriers, means for pivotally supporting said spindle carriers at the upper ends thereof on said rotating carrier, means for clamping the lower ends of said spindle carriers against said rotating carriers, a rotating spindle in each spindle carrier, a chuck mounted on each spindle, a coöperating can support for each chuck, a seaming roll mounted within a circle described by said rotating chucks and having its axis set eccentric to the axis of the rotating carrier, each spindle carrier having a receiver for the can body for centering the same underneath the chuck, a can end support for supporting a can end, and means for moving the can supports for causing the can bodies to engage the can ends and the can ends to engage the chucks.

spindle carriers, means for pivotally supporting said spindle carriers at the upper ends thereof on said rotating carrier, means for clamping the lower ends of said spindle carriers against said rotating carriers, a rotating spindle in each spindle carrier, a chuck mounted on each spindle, a co-operating can support for each chuck, a seaming roll mounted within a circle described by 5 said rotating chucks and having its axis set eccentric to the axis of the rotating carrier, each spindle carrier having a receiver for the can body for centering the same underneath the chuck, a can end support for supporting a can end, means for moving the can supports for causing the can bodies to engage the can ends and the can ends to engage the chucks, said carrier having a supporting table with recesses therein for said 10 can supports whereby the upper surface of 15 20

the can supports are flush when lowered with the upper surface of the table, a cam for raising and lowering the can supports, means for adjusting the position of said cam, and a filling ring for the openings there- 25 through adapted to be placed on the table for raising the surface of the table so that the same will be flush with the upper faces of the can supports when lowered and in their adjusted positions. 30

In testimony whereof, we affix our signatures, in the presence of two witnesses.

IVAR F. WARME.
JOHN C. TALIAFERRO.

Witnesses for Mr. Warme:

F. M. BONTA,
F. M. GORDON.

Witnesses for Mr. Taliaferro:

W. A. CRANWELL,
HENRY J. MUELLER.
